(57) **CLAIM**

The ornamental design for an LED lamp, as shown and described.

DESCRIPTION

FIG. 1 is a top perspective view of an LED lamp showing our new design;

FIG. 2 is a front view thereof;

FIG. 3 is a rear view thereof;

FIG. 4 is a top view thereof;

FIG. 5 is a bottom view thereof;

FIG. 6 is a right-side view thereof;

FIG. 7 is a left-side view thereof;

FIG. 8 is a cross-sectional view taken along line 8-8 in FIG. 2, in which the internal mechanism is omitted; and,

FIG. 9 is another top perspective view thereof, in which the pale gray portion is a light emitting portion.
